MULTIPLE CUP HOLDING DEVICE

Arthur J. Traumüller, Brooklyn, N.Y.

Application April 28, 1948, Serial No. 23,753

10 Claims. (Cl. 211—115)

1

This invention relates to devices for holding a plurality of cups for suspension beneath a shelf or other horizontal support. More particularly, the invention deals with a device of this kind having a central axis about which the device is free to rotate, so as to bring the cups suspended from the device, successively into accessible position for removal.

The novel features of the invention will be best understood from the following descriptions when taken together with the accompanying drawing, in which certain embodiments of the invention are disclosed, and in which the separate parts are designated by suitable reference characters in each of the views, and in which:

Fig. 1 is a plan view of the device, indicating a number of cups suspended therefrom.

Fig. 2 is a section on the line 2—2 of Fig. 1, showing the device attached to a shelf or other support, and omitting the cups.

Fig. 3 is a detailed view of a part of the device, indicating the manner of assemblage of the cup supporting members.

Fig. 4 is a section on the line 4—4 of Fig. 1, and

Fig. 5 is a section on the line 5—5 of Fig. 1.

It has been customary to provide what have been generally termed as cup hooks for supporting cups, as well as other articles from a shelf or similar support, and in some instances, devices of this type and kind have been made with means for retaining the article against displacement from the supporting hook.

The object of my present invention is to provide a cup or article supporting device in the form of a rotatably mounted plate or disc having thereon, a plurality of cup or article engaging elements, whereby a plurality of cups or other articles can be supported in nested or compact relationship to each other, while at the same time, rendering each article accessible for removal by rotation of the disc.

In the construction shown, the device comprises a disc or plate 10, of any suitable sheet material, and here metal or plastic materials can be employed. The sheet is suitably shaped to form a central upwardly extending domed portion 11, having a depressed apertured portion 12 for the reception of a screw or other fastening and mounting member 13. At the periphery of the disc, is an upstanding annular flange 14, which is cut or severed at four equally spaced intervals, as at 15, note Fig. 1. The cuts at 15 register with apertures 16 in the flange 14 for reception of sliding rods 17.

2

As each rod 17 is of the same construction, the brief description of one will apply to all. However, to distinguish these rods one from the other, the hook or hanger end portions thereof will be defined as 18—18a—18b and 18c. These rods also have at their inner end portions, fingerpieces identified as 19—19a—19b and 19c. The hook or hanger ends 18—18c are shaped to extend angularly to the rod 17, in the manner clearly illustrated in Fig. 1 of the drawing, so as to support four cups, indicated at 20—20a—20b and 20c suspended from the hooks or hangers 18 to 18c respectively. By this arrangement, the open end of one cup is disposed substantially at right angles to the side of an adjacent cup, thus producing the compact nesting, indicated in Fig. 1, and facilitates a reasonable amount of swinging of each cup, without danger of clashing into another cup. From Fig. 1, it will appear that the peripheral outer or lip edge of one cup is disposed to swing within the opening of the adjacent cup. Considering Fig. 1 of the drawing, it will also be apparent that the hooks or hangers 18—18c, when in operative position, are normally within the boundaries of the disc, except for a small protruding portion thereof. The hooks extend onto the lower surface of the disc and in conjunction with this lower surface, the loops of the hooks are closed, thus positively retaining the cups against displacement. However, by pushing outwardly on the fingerpieces 19—19c, the hooks 18—18c are brought beyond the limit of the flange edge 14 of the disc to freely open the hooks 18—18c for attachment and detachment of the cups.

In addition to the guide of the rod 17 in the apertures 16, the rods are further guided in other apertures 21 of upwardly extending bearing portions 22 formed integrally with the plate 10. In fashioning the device from sheet material, the bearings 22 will form rather large openings 23 in the sheet, and these openings register with elongated openings 24 in which the fingerpieces 19—19c operate in movement of the hooks 18—18c from the closed, to the open position and vice versa.

The apertures 24 are bordered by flange portions 25, note Fig. 5, which aid in concealing coil springs 26, which are arranged upon the rods 17 between the bearings 22 and the fingerpieces 19—19c. As the structure of each pin, including its support with the spring thereon, and the apertures in which the fingerpieces are mounted, is the same in all instances, the brief description of one will apply to all. At the base of the finger-

pieces 19—19^c are formed enlarged portions 27 which retain the springs 26 against displacement from the pins, or in other words, act as stops for the corresponding ends of the spring.

In making the device of sheet material, it is 5 desirable, particularly in using thin sheet material, to reinforce the disc, and this is accomplished by a circumferential bead 28 at the inner portion of the disc adjacent the dome 11, and an outer peripheral bead 29, adjacent the 10 flange 14. These two annular beads are joined at circumferentially spaced intervals by radial ribs 30.

It will be apparent from a consideration of Fig. 1 of the drawing, that the pins or rods 17 15 are mounted radially with respect to the axis 13. It will thus be apparent, that in operating the pins 17 to extend the hooks 18—18^c outwardly in removal or attachment of the cups, the strain 20 is radially and direct upon the axis, thereby maintaining the disc in position and against any rotary movement.

From a standpoint of assemblage, it will be apparent, that the pins with the springs mounted thereon can be assembled as a unit by extending the split walls of the flange 14, substantially as seen at 14' in Fig. 3 of the drawing and in splitting the bearings 22, as at 31 and flaring the walls thereof, as indicated at 22' and then after assemblage of the pins, returning these parts to 30 their normally aligned position. It is also preferred that the dome 11 be slightly greater in depth than the flange 14, so that a slight clearance will be provided between the flange and the shelf or support 32. At least, it is preferred that a non-binding engagement be provided at this position so that the disc can be turned by hand in a free manner in swinging any of the cups in position for removal. It will be apparent that the device can be mounted on shelves where the shelf width is within the greatest diameter of the cups as arranged on the device. In other words, the greatest over-all width of the hung cups, as seen in Fig. 1 of the drawing. It will be apparent that the device may be utilized to hang any desired number of cups, and may be utilized for hanging articles of any type or kind.

Having fully described my invention, what I claim as new and desire to secure by Letters Patent is:

1. A multiple cup holding device of the character described comprising a disc, means centrally of the disc for attachment of the device to a support, a plurality of rods slidably mounted on the disc at circumferentially spaced intervals, one end portion of the rods having hanger hooks arranged upon the lower surface of the disc, the other end portion of the rods having fingerpieces extending downwardly through apertures in said disc, spring means on the rods cooperating with means on the disc to normally support the hanger hooks substantially within peripheral boundaries of the disc, and said hanger hooks being adapted to extend beyond peripheral boundaries of the disc by actuation of the rods by said fingerpieces against the action of said spring means.

2. A multiple cup holding device of the character described comprising a disc, means centrally of the disc for attachment of the device to a support, a plurality of rods slidably mounted on the disc at circumferentially spaced intervals, one end portion of the rods having hanger hooks arranged upon the lower surface of the disc, the

other end portion of the rods having fingerpieces extending downwardly through apertures in said disc, spring means on the rods cooperating with means on the disc to normally support the hanger hooks substantially within peripheral boundaries of the disc, said hanger hooks being adapted to extend beyond peripheral boundaries of the disc by actuation of the rods by said fingerpieces against the action of said spring means, the disc having elongated apertures in alignment with the rods, and said fingerpieces extending through and operating in said apertures.

3. A multiple cup holding device of the character described comprising a disc, means centrally of the disc for attachment of the device to a support, a plurality of rods slidably mounted on the disc at circumferentially spaced intervals, one end portion of the rods having hanger hooks arranged upon the lower surface of the disc, the other end portion of the rods having downwardly extending fingerpieces projecting from the lower surface of said disc, spring means on the rods cooperating with means on the disc to normally support the hanger hooks substantially within peripheral boundaries of the disc, said hanger hooks being adapted to extend beyond peripheral boundaries of the disc by actuation of the rods by said fingerpieces against the action of said spring means, the disc having elongated apertures in alignment with the rods, said fingerpieces extending through and operating in said apertures, and the walls of said apertures having downwardly extending side flanges.

4. A multiple cup holding device of the character described comprising a disc, means centrally of the disc for attachment of the device to a support, a plurality of rods radially mounted on the disc at circumferentially spaced intervals, one end portion of the rods having hanger hooks arranged upon the lower surface of the disc, the other end portion of the rods having downwardly extending fingerpieces projecting from the lower surface of said disc, spring means on the rods cooperating with means on the disc to normally support the hanger hooks substantially within peripheral boundaries of the disc, said hanger hooks being adapted to extend beyond peripheral boundaries of the disc by actuation of the rods by said fingerpieces against the action of said spring means, the disc having elongated apertures in alignment with the rods, said fingerpieces extending through and operating in said apertures, and the walls of said apertures having downwardly extending side flanges.

5. A multiple cup holding device of the character described comprising a disc, means centrally of the disc for attachment of the device to a support, a plurality of rods radially mounted on the disc at circumferentially spaced intervals, one end portion of the rods having hanger hooks arranged upon the lower surface of the disc, the other end portion of the rods having downwardly extending fingerpieces projecting from the lower surface of said disc, spring means on the rods cooperating with means on the disc to normally support the hanger hooks substantially within peripheral boundaries of the disc, said hanger hooks being adapted to extend beyond peripheral boundaries of the disc by actuation of the rods by said fingerpieces against the action of said spring means, the disc having elongated apertures in alignment with the rods, said fingerpieces

extending through and operating in said apertures, the walls of said apertures having downwardly extending side flanges, the periphery of the disc having an upwardly extending flange portion in which the rods are slidably mounted, and means reinforcing the disc intermediate the rod sections thereof.

6. A multiple cup holding device of the character described comprising a disc, means centrally of the disc for attachment of the device to a support, a plurality of rods radially mounted on the disc at circumferentially spaced intervals, one end portion of the rods having hanger hooks arranged upon the lower surface of the disc, the other end portion of the rods having downwardly extending fingerpieces projecting from the lower surface of said disc, spring means on the rods cooperating with means on the disc to normally support the hanger hooks substantially within peripheral boundaries of the disc, said hanger hooks being adapted to extend beyond peripheral boundaries of the disc by actuation of the rods by said fingerpieces against the action of said spring means, the disc having elongated apertures in alignment with the rods, said fingerpieces extending through and operating in said apertures, the walls of said apertures having downwardly extending side flanges, the periphery of the disc having an upwardly extending flange portion in which the rods are slidably mounted, and means reinforcing the disc intermediate the rod sections thereof and the peripheral and axial portions of said disc.

7. A device of the character described comprising a disc having a central upwardly domed portion, an upwardly extending circumferential flange, the disc having circumferentially spaced radial apertures between the dome and flange portions thereof, upwardly extending bearings at the outer ends of said apertures, the peripheral flange having apertures in alignment with the first named apertures and said bearings, rods slidably mounted in the bearings and extending through the apertures of said peripheral flange, outer ends of the rods having downwardly, inwardly and angularly extending suspending hooks normally arranged upon the lower surface of the disc, inner ends of the rods having downwardly extending fingerpieces operating in the radial apertures of said disc, and springs on said rods between the fingerpieces and said bearings and adapted to normally retain the suspending hooks under the lower surface of said disc.

8. A device of the character described comprising a disc having a central upwardly domed portion, an upwardly extending circumferential flange, the disc having circumferentially spaced radial apertures between the dome and flange portions thereof, upwardly extending bearings at the outer ends of said apertures, the peripheral flange having apertures in alignment with the first named apertures and said bearings, rods slidably mounted in the bearings and extending through the apertures of said peripheral flange, outer ends of the rods having downwardly, inwardly and angularly extending suspending hooks normally arranged upon the lower surface of the disc, inner ends of the rods having downwardly extending fingerpieces operating in the radial

apertures of said disc, springs on said rods between the fingerpieces and said bearings and adapted to normally retain the suspending hooks under the lower surface of said disc, and means for reinforcing said disc.

9. A device of the character described comprising a disc having a central upwardly domed portion, an upwardly extending circumferential flange, the disc having circumferentially spaced radial apertures between the dome and flange portions thereof, upwardly extending bearings at the outer ends of said apertures, the peripheral flange having apertures in alignment with the first named apertures and said bearings, rods slidably mounted in the bearings and extending through the apertures of said peripheral flange, outer ends of the rods having downwardly, inwardly and angularly extending suspending hooks normally arranged upon the lower surface of the disc, inner ends of the rods having downwardly extending fingerpieces operating in the radial apertures of said disc, springs on said rods between the fingerpieces and said bearings and adapted to normally retain the suspending hooks under the lower surface of said disc, and said bearings and the peripheral flange of the disc having means facilitating attachment of the rod units with said disc.

10. A device of the character described comprising a disk having a central upwardly domed portion, an upwardly extending circumferential flange, the disc having circumferentially spaced radial apertures between the dome and flange portions thereof, upwardly extending bearings at the outer ends of said apertures, the peripheral flange having apertures in alignment with the first named apertures and said bearings, rods slidably mounted in the bearings and extending through the apertures of said peripheral flange, outer ends of the rods having downwardly, inwardly and angularly extending suspending hooks normally arranged upon the lower surface of the disc, inner ends of the rods having downwardly extending fingerpieces operating in the radial apertures of said disc, springs on said rods between the fingerpieces and said bearings and adapted to normally retain the suspending hooks under the lower surface of said disc, said bearings and the peripheral flange of the disc having means facilitating attachment of the rod units with said disc, and the elongated apertures being bordered by downwardly extending side flanges.
